SURFACE ORNAMENTATION OF WALLS.

No. 16,861.

Patented Aug. 17, 1886.

UNITED STATES PATENT OFFICE.

FREDERICK MANKEY, OF WILLIAMSPORT, PENNSYLVANIA.

DESIGN FOR SURFACE ORNAMENTATION OF WALLS.

SPECIFICATION forming part of Design No. 16,861, dated August 17, 1886.

Application filed July 1, 1886. Serial No. 906,865. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph, forming part hereof.

My design consists of the elongated diamond-shaped elevation A, parallel to each side of which are elongated elevations B, arranged in groups of three. The said elevations B have rounded upper surfaces. At the corners or angles of the diamond A are groups C of small

diamond-shaped pyramidal elevations, each 15 group containing nine of said small diamonds.

I claim—

The design for surface ornamentation of walls, &c., which consists of the elongated diamond-shaped elevations A, the groups B, each 20 composed of three parallel elevations having rounded upper surfaces, and the four groups C of small diamond-shaped elevations, substantially as herein shown and described.

FREDERICK MANKEY.
